UNITED STATES PATENT OFFICE.

WILLIS H. CARRIER, OF ESSEX FELLS, NEW JERSEY, ASSIGNOR, BY MESNE ASSIGNMENTS, TO CARRIER CONSTRUCTION COMPANY, INC., OF NEWARK, NEW JERSEY.

RADIATOR OR HEATER.

Application filed January 25, 1923. Serial No. 314,831.

This invention relates more particularly to tubular radiators or heaters of that kind comprising opposite headers connected by radiating tubes through which steam or other medium is caused to flow and which are spaced apart to permit air or other medium to pass between or around the tubes. The change in temperature which can be produced by such a heater or radiator, other things being equal, depends upon the number of successive rows or groups of tubes that it has. As an illustration, a heater having four rows of tubes, one behind another, is adapted to produce approximately a 100° rise in temperature of air passing through the heater. It is desirable, however, in some classes of work, for instance in the heating of public buildings, to be able to graduate the effect of the heater so as to give, for example, different heating effects of say 25°, 50°, 75° or 100° or thereabouts. This would not be commercially practical with a heater having a plurality of rows or groups of tubes all controlled by the same valve or valves. Such results could be obtained by the use of four complete one-row heaters, but a plurality of one-row heaters is expensive on account of the separate headers, pipe connections and valves required for each heater. A single-row heater is also poor mechanically on account of having to depend upon a frame, casing or bracing means in addition to the tubes to give the required rigidity in the heater.

One object of this invention is to produce a practical and efficient tubular radiator or heater having a plurality of rows or groups of radiating tubes, for instance four rows of such tubes, all of which connect with the same headers, so that only two headers are required for all of the tubes, and to provide the heater or radiator with controlling means whereby any one or more of the rows of tubes can be cut off or utilized so as to enable the heating effect of the radiator or heater to be graduated in accordance with the number of rows or groups of tubes of which it is composed. Other objects are to so construct a multiple-row or group tubular radiator or heater that the minimum number of valves and pipe connections are required to enable the use of any one or more of the rows or groups of tubes; and more specifically to provide a heater or radiator having four rows or groups of radiating tubes in which

the headers are constructed so that by the use of only two valves for each header it is possible to use either one, two, three or four of the rows or groups of tubes, as may be desired; and also to improve tubular radiators or heaters in the other respects hereinafter described and set forth in the claims.

In the accompanying drawings:

Fig. 1 is an elevation of a radiator or heater comprising two units, embodying my invention.

Fig. 2 is a plan view thereof.

Fig. 3 is a fragmentary horizontal section of the upper header and valve box thereof, on an enlarged scale.

Fig. 4 is a transverse sectional elevation on line 4—4, Fig. 1 on a still larger scale.

Fig. 5 is a fragmentary longitudinal vertical section on line 5—5, Fig. 3, of the upper valve box and adjacent portion of the header.

Fig. 6 is a fragmentary transverse vertical section of the valve box on line 6—6, Fig. 3.

The radiator or heater illustrated and described in this application as a practical embodiment of my invention is primarily designed as a steam heater, steam being used in the radiating tubes for heating air which is caused to pass over the external surfaces of the tubes, but the invention is not necessarily restricted in application to steam heaters for heating air since radiators embodying the invention are adapted for use either for heating or cooling purposes, depending upon the relative temperatures of the medium flowing through the tubes and the medium which contacts with the external surfaces of the tubes.

The radiator comprises parallel, spaced radiating tubes 10 preferably arranged vertically and connected at their ends to opposite, or upper and lower, headers 11 and 12, which are respectively connected with suitable inlet and outlet pipes 13 and 14, so that steam or other medium admitted to one of the headers is adapted to pass through the radiating tubes to the other header and discharge through the outlet pipe 14 connected with the latter header. The radiator tubes are preferably thin tubes of brass or other metal of high conductivity, provided with radiating fins formed by thin strips or ribbons of brass or the like wound helically around the tubes and soldered or brazed thereon. Tubes of any other con-

struction adapted to give the required radiation can be used, however. These tubes are arranged in a plurality of rows or groups, for instance as shown in the radiator 5 illustrated, in four parallel rows, one behind another, the tubes in one row being preferably arranged opposite the spaces between the tubes in the next row so as to better insure contact of the air or other external medium with all of the tubes of the radiator. Each header consists of a hollow shell or casting 15 having an opening 16 extending along one side thereof, and a flexible tube plate 17 which closes the opening 10 of the shell, and is provided with holes in which the radiating tubes 10 are secured, preferably by a driving fit in lips or flanges surrounding the holes. This tube plate is 15 preferably a thin plate or sheet of brass or of the same metal as the radiating tubes. In the construction shown, the header shell 15 consists of a rigid casting provided with lateral flanges 18 bounding the opening 16 and the tube plate is 20 bolted at its edges to these flanges, a suitable packing or gasket being interposed between the tube plate and the shell flanges to insure a steam-tight joint. Bolting or clamping pieces 19 are also preferably employed at the outer face of the tube plate for 25 the bolts to bear upon to insure a strong and secure connection between the tube plate and header shell. The headers are also shown as being formed with end bolting flanges 30 20, and preferably the opposite ends of each header have the same form and the upper and lower headers are alike, thereby enabling the parts to be interchanged and reversed. When the radiator consists of only one unit 40 or section constructed as described, one end of each header 11 and 12 is closed by a suitable cap plate or closure 21 bolted to the flange at this end of the header and a valve box or pipe connection is similarly secured to 45 the opposite end of each header for the connection of the inlet or outlet pipe 13 or 14, these valve boxes or connections 22 and 23 being provided with valves, as hereinafter explained, for controlling the flow of the 50 steam or other medium through the radiator. Radiators of different desired lengths can be made by joining together end to end two or more such units of the same or different lengths, by means of bolts connecting 55 the end flanges of the headers of the sections or units. In such a multiple-unit radiator the outer ends of the headers at one end of the radiator are closed by cap plates 21, while the valve boxes or pipe connections are 60 provided at the outer ends of the headers at the other end of the radiator.

The shell 15 of each of the headers is divided into a plurality of compartments extending lengthwise of the header by longitudinal webs or partitions 24 which extend

from the outer wall of the shell to and are adapted to bear at their edges against the tube plate 17. In the radiator shown, in which the tubes are arranged in four rows, each header is provided with two such partitions dividing the header into three longitudinal compartments, the partitions being so disposed that one row of tubes connects with each outer compartment of the headers and the remaining two central rows of tubes connect with the central compartments of the headers. The partitions extend from end to end of the headers so that there is no communication between the tubes connecting with different compartments of the headers except through the valve box or pipe connection 22 or 23. 70 75 80

The valve box or pipe connection for each header, like the header, is divided by webs or partitions 25 into compartments 26, 27 and 28 each communicating with a separate compartment of the header. The valve boxes 22 and 23 are alike except that the discharge box 23 can be, and is shown as smaller, since it is not necessary for this box to be as large 90 as the supply or inlet valve box in a steam heater. Two hand valves 29 and 30 of any suitable construction control two of the compartments of the valve box, these valves preferably being arranged to seat upon two valve seats at the outer ends of the two compartments 26 and 27 so that when the valves are seated these two compartments are cut off from the third compartment 28 of the valve box and from a chamber 31 in the valve 100 box with which the inlet or outlet pipe connects. Said third compartment 28 of the valve box is always in open communication with the chamber 31 and when the two valves are closed as shown in Fig. 3, the 105 steam or other medium can pass from the supply pipe 13 only into the outer compartment 28 of the upper valve box 22 and thence through the communicating compartment of the upper header and the connecting outer row of tubes 10 into the corresponding compartments of the lower header and discharge valve box and out through the discharge pipe 14. Thus when both valves are 110 closed the steam or other medium passes only through one row of the tubes and only this row is active, the remaining rows of tubes being shut off. If it is desired to utilize two rows of tubes, the inlet and outlet valves 29 are opened thereby admitting the steam or 115 medium to the other outer row of tubes so that then the two outer rows of tubes will be supplied with the steam or other medium and these two rows will be active while the remaining tubes are inactive. In order to use three rows of the tubes said valves 29 are closed and the inlet and outlet valves 30 controlling the central compartments of the valve boxes are opened and the steam or medium will then be admitted to the two cen- 120 125 130

tral rows of tubes and the third row of tubes which connects with the open compartments 28 of the valve boxes. In order to use all four rows of the tubes, both of the valves 29 and 30 for each header are opened when the steam or medium will be admitted to all four rows of tubes.

By the construction described it will be seen that with only two inlet and two outlet valves it is possible to utilize one, two, three or four rows of the tubes, as may be required, and it is not necessary to provide an inlet and an outlet valve for each row of tubes as would be necessary in the case of a plurality of single-row heaters in which each row of tubes has its separate inlet and outlet header. When it is desired to entirely shut off the heater, this can be done by closing the usual valve (not shown) in the supply pipe.

If the steam or other medium is admitted to a part only of the rows of tubes, there will be a difference in the expansion and contraction of these tubes and of the remaining rows of tubes to which the steam or medium is not admitted, but the tube plates 17 by which the tubes are connected to the headers are flexible and permit such unequal expansion and contraction of the tubes in the different rows. The partition webs 25 of the headers are held in firm contact with the tube plates by suitable tension devices 32 at opposite sides of the radiator which tend to draw the opposite headers towards each other, so that when such unequal expansion of the tubes in different rows occurs, the tube plates can flex over the inner edges of the partition webs which will thus maintain a closure between the adjacent compartments of the headers and prevent the escape of the steam or medium from one compartment to the other notwithstanding the inequality in the expansion of the tubes in the different rows. For example, when one of the outer rows of tubes is heated and expands more than the remaining tubes the tension devices connecting the headers at this side of the radiator will permit the headers to spread apart at this side under the expansion of the tubes, and the tube plates 17 will be drawn tightly against the inner edges of the adjacent partitions and prevent communication between the outer and middle compartments of the headers. Likewise when the two outer rows of tubes expand to a greater extent than the two inner rows, the opposite edges of the tube plates will flex and the plate will be drawn taut against the edges of the header partitions. If the steam is admitted to the two central rows of tubes and not to the two outer rows, thus causing greater expansion of the two inner rows, the central portions of the tube plates can flex with the expansion of the tubes, thus drawing or holding

the tube plates taut against the edges of the two partitions of each header. Irrespective of which of the rows are heated and expanded and irrespective of whether one or more than one row of tubes is or are heated, the flexible tube plates with the headers constructed and connected as described, will insure firm bearing of the tube plates against the inner edges of the header partitions and a tight closure between the adjacent compartments of each header.

The tension devices 32 shown in the drawings, consist of rods secured by nuts to the flanges of one header and passing loosely through holes in the flanges of the other header, springs 33 surrounding the rods between the latter flanges and nuts 34 screwed on the rods. The movement of the headers towards each other by the springs is limited by screw nuts 35 on the rods and engaging the inner faces of the bolting pieces. The nuts 34 can be adjusted to regulate the spring pressure on the headers. Any other tension means suitable for the purpose could be used.

I claim as my invention:—

1. A tubular radiator comprising a plurality of groups of radiating tubes, a header having a plurality of separate compartments each communicating with a different group of said tubes and each having open ends at opposite ends of the header, a removable closure for closing said compartments at one end of the header, and a pipe connection attached to the other end of the header and provided with valves for causing the flow of a medium through one or more of said compartments and the communicating group or groups of radiating tubes.

2. A tubular radiator comprising a plurality of groups of radiating tubes, a header having a plurality of separate compartments each communicating with a different group of said tubes and each having open ends at opposite ends of said header, a removable closure for closing said compartments at one end of the header, a pipe connection which forms a closure for said compartments at the other end of the header, said pipe connection being provided with a fluid inlet and with compartments each communicating with one of the header compartments, and valves for opening and closing communication between said inlet and one or more of said compartments in the pipe connection.

3. A tubular radiator comprising a plurality of groups of radiating tubes, a header having a plurality of separate compartments each communicating with a different group of said tubes, a pipe connection provided with a fluid inlet and with compartments each communicating with one of the header compartments, one of the compartments

ments of said pipe connection being in open communication with said fluid inlet, and valves for opening and closing communication between said fluid inlet and said other 5 compartments of the pipe connections.

4. A tubular radiator comprising four groups of radiating tubes, a header having three separate compartments, one communicating with two of said groups of tubes 10 and each of the two remaining compartments communicating with one of said groups of tubes, a fluid connection for said header in open communication with one of the two last mentioned compartments of the 15 header, and two valves for opening and closing communication between said inlet and the other two compartments of the header.

5. A tubular radiator comprising a plurality of radiating tubes, a header for said 20 tubes comprising a shell open along one side and a flexible tube plate which closes the open side of the shell and in which the tubes are secured, said tube plate being adapted to flex due to the expansion and 25 contraction of the radiating tubes said shell having a longitudinal partition which bears along one edge against said tube plate whereby said partition and tube plate divide the header into separated compartments 30 each communicating with a portion only of said tubes.

6. A tubular radiator comprising a plu-

rality of radiating tubes, a header for said tubes comprising a shell which is open along one side and is formed with one or 35 more integral partitions each having one edge extending along the open side of the shell, and a flexible tube plate in which the tubes are secured and which is secured to the periphery of said shell and bears 40 against the edge of each partition to form a plurality of separated compartments in the header each communicating with a portion only of the tubes, said radiator having provision for retaining said tube plate 45 in contact with said partition for preventing communication between said compartments.

7. A tubular radiator comprising a plurality of radiating tubes, headers for the opposite ends of said tubes, each header comprising a shell which is open along one side and is formed with a partition having one edge extending along the open side of the shell, and a flexible tube plate in which the 50 tubes are secured and which closes the open side of the shell and is adapted to bear against the edge of said partition to form a plurality of compartments in the header, each communicating with a portion only of 55 the tubes, and tension means acting on said headers to hold said partitions against said tube plates.

WILLIS H. CARRIER.
